UNITED STATES PATENT OFFICE.

WALTER LOCKHART COWEN AND CLIVE ALFRED FRIEND, OF SYDNEY, NEW SOUTH WALES, AUSTRALIA, ASSIGNEES TO LEOPOLD ROGALY, OF SYDNEY, NEW SOUTH WALES, AUSTRALIA.

AUTOMATIC STARTING AND STOPPING ATTACHMENT FOR DISK-TYPE TALKING MACHINES.

Application filed December 15, 1921. Serial No. 522,693.

To all whom it may concern:

Be it known that WALTER LOCKHART COWEN and CLIVE ALFRED FRIEND, subjects of the King of Great Britain and Ireland, residing at Sydney, New South Wales, Australia, have invented certain new and useful Improvements in Automatic Starting and Stopping Attachments for Disk Type Talking Machines, of which the following 10 is a specification.

This invention relates to means for automatically starting the rotation of the table of a disk type talking machine and for arresting the rotation of the table when the 15 reproducer needle has attained the final course of the record groove.

The attachment is located on the floor between the reproducer arm bearing and the outer periphery of the rotating table carrying the disk record, and the attachment comprises a mechanical device operated by the lateral movement of the reproducer arm and functioning to bring a spring controlled 20 brake into engagement with the table rim.

The device consists of a plunger slidably mounted in fixed bearings and having on one end a shoe of leather, rubber or other frictional material. The plunger is controlled by a coil spring which normally acts 25 to move the plunger outwards to bring the brake shoe into contact with the rim of the table. The plunger is moved in a rearward direction to release the brake shoe from contact with the table rim by means of a 30 pawl depending from the reproducer arm neck which engages a helical slot formed at the rear end of the sliding plunger. A hinged spring controlled detent engages 35 with a slot formed in the side of plunger 40 and holds the plunger in the rearward position with the brake shoe clear of the table. The plunger is released by means of a striking finger attached to the neck of reproducer arm which engages the hinged detent 45 when the reproducer arm has moved into a predetermined position and the brake shoe immediately comes into contact with the table rim, and stops the rotation of same.

50 But in order that the invention may be clearly understood reference will now be made to the drawings which accompany and

form part of this complete specification and in which:—

Figure 1 is a perspective view showing the 55 device in position with brake shoe in engagement with the table rim and the operating pawl in position ready to withdraw the plunger.

Figure 2 is a similar view showing the 60 plunger withdrawn and striking finger about to engage the hinged detent.

Figure 3 is a perspective view of covering cap.

Figure 4 is a perspective view of device 65 from the opposite angle.

Figure 5 is a similar view to Figure 4 showing covering cap in position.

Figure 6 is a diagrammatic view illustrating the operation of the device. 70

The plunger A is slidably mounted in bearings 7 and has on its forward end a friction brake shoe 8. The plunger A is normally held in the forward position as shown in Figure 1 by the coil spring 9, 75 and is moved rearwards by means of an operating pawl B which depends from a collar 10 which is clamped to the neck 11 of the reproducer arm 12. The pawl B is adapted on the lateral movement of the 80 reproducer arm to engage a helical slot 13 and move the plunger in the rearward direction clear of engagement with the table 14. As soon as the plunger A has been moved rearwards the hinged detent C 85 springs into engagement with the notch 15 and holds the plunger in the rearward position. The detent C is pivoted at 16 to bearing plate 7 and abuts on one side against the plunger A and on the other against plate 90 17 with intermediate leaf spring 18. The device is secured to the floor by screw studs 19 with adjusting nuts 20 and has a covering cap 21 as shown in Figures 4 and 5. A rotatable striking finger 22 is mounted on 95 collar 10 in a position to engage the detent C in the manner hereinafter described.

The operation is as follows referring to Figure 6. In adjusting the stopping device the needle 23 on speaker 24 is placed in the 100 "finish" groove 25 of disk record 26 and the striking finger 22 is rotated until it comes into contact with the detent C which is in its normal position. The reproducer

arm is then swung back, the operating pawl B riding freely over the helical slot 13. The motor should then be wound up. In starting the machine the reproducer arm 12 should be brought forward in the ordinary manner and the needle 22 placed in the "start" groove 27 of record 26. In doing this the operating pawl B engages the helical slot 13 and moves the plunger A rearward thus releasing the brake and allowing the table to rotate, the plunger being held by the detent C. When the needle is running in the "finish" groove 25 the striking finger 22 comes into contact with the hinged 15 detent C and releases the plunger and the brake shoe 8 engages and stops the rotation of the table.

We claim:

1. An improved automatic starting and stopping attachment for disk type talking machines comprising a slidably mounted plunger having at one end a friction brake shoe and the other end a helical groove, a coil spring controlling said plunger, said plunger being provided with a notch, a pawl depending from the producer arm neck adapted to engage said helical groove, a

hinged spring controlled detent adapted to engage said notch and an adjustable finger attached to the reproducer arm and adapted to engage said detent substantially as and for the purpose herein set out.

2. An improved automatic starting and stopping attachment for disk type talking machines as set out in claim 1 in which said pawl is attached to a band clamped to the neck of the reproducer arm of the machine.

3. An improved automatic starting and stopping attachment for disk type talking machines as set out in claim 1 in which said finger is attached to a band clamped to the neck of the reproducer arm and is adapted to make contact with said hinged detent when the reproducer arm is in a predetermined position substantially as herein described and illustrated in the drawings.

In testimony whereof they have affixed their signatures in presence of two witnesses.

WALTER LOCKHART COWEN,
CLIVE ALFRED FRIEND.
